UNITED STATES PATENT OFFICE

156,071

DESIGN FOR A WATCH

Frederick C. Bruns, Forest Hills, N. Y.

Application July 28, 1948, Serial No. 147,810

Term of patent 14 years

(Cl. D42—8)

To all whom it may concern:

Be it known that I, Frederick C. Bruns, a citizen of the United States of America, residing at Forest Hills, in the county of Queens and State of New York, have invented a new, original, and ornamental Design for a Watch, of which the following is a specification, reference being had to the accompanying drawing, forming a part thereof.

In the drawing,

I claim:

The ornamental design for a watch, as shown.
FREDERICK C. BRUNS.
